UNITED STATES PATENT OFFICE.

NORMAN PRICE, OF BROOKLYN, NEW YORK.

FLUSH-TANK.

1,241,276.

Specification of Letters Patent. Patented Sept. 25, 1917.

Application filed January 24, 1917. Serial No. 144,149.

To all whom it may concern:

Be it known that I, NORMAN PRICE, a citizen of the United States, and a resident of the city of New York, borough of Brooklyn, in the county of Kings and State of New York, have invented a new and Improved Flush-Tank, of which the following is a full, clear, and exact description.

This invention relates to baths and closets and has particular reference to flush tanks for toilet bowls or other analogous purposes.

Among the objects of this invention is to provide a flush tank that will be practically non-leakable and provided with a valveless supply pipe connection.

Another object of the invention is to improve that type of flush tanks which have the charge of water maintained under pressure equal to the pressure of the supply leading to the building or from the building to the flush tank, whereby there is insured a prompt and rapid discharge of water from the tank for flushing purposes.

A further object of the invention is the provision of means coöperating with the valve mechanism to insure a proper refill of the toilet bowl.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like characters designate the same parts in the several views, and in which

Figure 1 is a vertical longitudinal section on the line 1—1 of Fig. 2;

Fig. 2 is a horizontal sectional view on the line 2—2 of Fig. 1; and

Fig. 3 is a vertical transverse section on the line 3—3 of Fig. 1.

Referring now more particularly to the drawings, I show a flush tank 10 of any suitable size, design or construction, but having sufficient strength to withstand the internal pressure to which it is adapted to be subjected. This tank is provided with a lid 11

and an internal horizontal partition 12 formed preferably as an integral part of the tank structure and provided with a sealing plug 13 at its center. The lid 11 provides a finish for the tank and prevents ordinary meddling or tampering with the sealing device below the stem.

14 indicates the main delivery or outlet spud for the tank, the same being fixed permanently at about the center of the bottom of the tank. This member 14 is locked in a water and airtight position with respect to the bottom of the tank by means of washers 15 and lock nuts 16 secured thereon in any common or approved manner.

An inlet pipe 17 leads into the interior of the tank at any desired place, but for convenience is indicated as leading through the bottom and is locked in a watertight manner thereto, but is provided with no valve for controlling the inlet of water.

A main valve 18 controlling the flush or delivery from the tank through the spud 14 is seated normally upon an annular valve seat 19 constituting the base of a frame or spider secured as by screw threads upon the upper end of the spud 14. Said spider includes a series of upwardly projecting arms 20 spaced from one another, permitting the free flow of water between them and out through the annular base or valve seat when the valve 18 is lifted from its normal closed position. The valve 18 is firmly and tightly secured to a stem 21 which extends both above and below the valve. The lower end of the stem 21 is slidably fitted in a guide member 22 fitted within the spud below the valve seat. This guide member is provided with large openings through which the water is adapted to flush freely. The upper end of the stem 21 is guided loosely through a hole 23 formed in the bottom of a cup 24 connected to and supported by the arms 20 of the frame above described. This cup and the other parts referred to associated therewith are of a size suitable for introduction into the interior of the tank through the hole normally closed by the plug 13. With the parts designed and arranged as thus far described, I may briefly state the manner

of operation as follows: The tank naturally is filled with air at the time of assemblage or after each flushing operation. When the tank is emptied of water, the valve 18 is closed, being so held by gravity acting upon it and its stem and also by the weight of a float ball 25 secured to the upper end of said stem and occupying a position within the cup 24. The inlet pipe 17 being open to the source of water supply, water flows freely into the tank until the internal pressure within the tank equals the pressure of the water supply. By this time, the body of air within the tank will be compressed into a cushion at the top of the tank and having a pressure equal to that of the water. The buoyancy of the float 25 is so proportioned that it will not lift the valve against the internal force tending to hold the valve closed until some outside influence initiates the opening action, but when the valve is once unseated the float will lift the valve to its open position by its buoyancy. When the valve is unseated and lifted by the float, the bulk of the water in the tank will be delivered promptly therefrom through the valve seat 19 and spud 14 by gravity assisted by the cushion of compressed air at the top. The valve, however, will be held open a little time so as to insure a proper refill of the toilet bowl. This temporary holding of the valve in its elevated position is effected by the comparatively small body of water held in the cup 24. The size of the hole 23, however, in the bottom of the cup is so designed that the water will flow from the cup following the discharge of the bulk of water from the tank, and this water from the cup together with the water admitted through the inlet during the interval between the delivery of the flushing water and the closing of the valve, will provide the refill for the bowl.

Any suitable means may be provided to unseat the valve 18 to discharge the contents of the tank. For this purpose I provide a rock shaft 26 journaled adjacent to one end in a stuffing box 27 in one side of the spud 14 below the tank and at its other end in a bracket 28, shown incidentally as carried by the inlet pipe 17. The inner end of the rock shaft or the end within the spud carries a cam 29 coöperating with the lower end of the stem 21 or an anti-friction roller 30 carried thereby and the other end of the rock shaft carries a lever 31 which when forced downwardly by the operator will lift the cam and unseat the valve. The roller 30 is indicated as being nearer to the guide member 22 than the valve is to the hole 23, and hence this roller may typify any suitable means to limit the upward movement of the valve so as to prevent the valve from obstructing the flow of water from the cup

through the hole 23. The lever may be maintained in its normal position by any suitable means, as a counterbalance so as not to interfere with the proper automatic seating of the valve 18 in the manner already set forth. The valve 18, as above premised, is guided for direct seating upon the seat 19 through the guides provided at 22 and 23, and since the only outlet from the tank is by way of the valve 18, the device is practically non-leakable and otherwise is of simple and effective construction in practice.

I claim:

1. In a flush tank, the combination of an outlet spud, a valve seat fixed upon the upper end thereof, a valve normally seated on said seat and guarding the delivery through the spud; said valve having a rigid stem extending above the valve, a float secured upon the upper end of said stem, a cup having a hole in its bottom through which said stem is guided; said cup being adapted to hold a predetermined quantity of water deliverable through said guide hole to provide for the refill of the bowl, supporting means for the cup extending from the valve seat, means to deliver water into the tank and cup; and means to unseat the valve to initiate the flow of water from the tank.

2. The combination with a flush tank and inlet and outlet pipes therefor, of valve mechanism controlling the delivery of water through the outlet pipe, said valve mechanism comprising a spider having a base secured upon the upper end of the outlet pipe and constituting a valve seat, said spider also including a plurality of upwardly projecting arms, a cup supported by said arms and having a hole in its bottom, a valve seated normally on said seat and having a rigid stem projecting upwardly through said hole into the cup, a float secured to the upper end of the stem within the cup and serving when the valve is unseated to lift it free from the seat allowing the bulk of the water in the tank to discharge through the outlet pipe, the cup and the hole in its bottom being so designed to provide for the water from the cup to follow the bulk of the water from the tank, and means acting through the outlet pipe to unseat the valve.

3. The combination of a flush tank including an airtight top having a sealing plug, a valveless inlet pipe leading into the tank, a delivery spud fitted into the bottom of the tank in alignment with said plug, a guide member fitted centrally in the spud, a valve seat fitted upon the upper end of the spud and having upwardly projecting arms, the valve seat and the arms constituting a spider adapted to be introduced into the tank through the top, a cup supported upon the

arms and having a guide hole in its bottom, a normally closed valve coöperating with said seat and having a rigid stem extending both above and below the valve and guided 5 in said guide member and cup hole, a float connected to the upper end of the valve stem within the cup, and means to unseat the

valve comprising a rock shaft journaled in the side of the spud and a cam secured to the inner end of the rock shaft and adapted 10 to coöperate with the lower end of the valve stem.

NORMAN PRICE.
